UNITED STATES PATENT OFFICE.

CHARLES E. TOMLINSON, OF SYRACUSE, NEW YORK, ASSIGNOR TO ALEXANDER T. BROWN,
OF SYRACUSE, NEW YORK.

TYPE-WRITING MACHINE.

No. 920,221.

Specification of Letters Patent. Patented May 4, 1909.

Application filed October 18, 1906. Serial No. 339,515.

To all whom it may concern:

Be it known that I, CHARLES E. TOMLINSON, citizen of the United States, and resident of Syracuse, in the county of Onondaga and State of New York, have invented 5 certain new and useful Improvements in Type-Writing Machines, of which the following is a specification.

My invention relates to typewriting machines and more particularly to means for guiding the type bar and also to repulsing means for causing the type bar to move rapidly from the platen after each imprint.

The object of my invention is to provide 15 simple and efficient means for the purposes stated.

To the above and other ends which will hereinafter appear, my invention consists in the features of construction, arrangements 20 of parts and combinations of devices set forth in the following description and particularly pointed out in the appended claims.

In the drawings, Figure 1 is an enlarged detail side elevation showing a type bar and 25 mounted hanger embodying my invention, a platen being shown diagrammatically. Fig. 2 is a detail top plan view of the type bar. Figs. 3 and 4 are detail transverse sectional views of the type bar, the sections 30 being taken on the line x—x of Fig. 2, the views showing respectively the arrangement of the parts just before and just as the type bar reaches the printing position, and in co-operation with the fixed guide on the hanger. 35 Fig. 5 is an enlarged detail sectional view corresponding to Fig. 4 but showing a modified form of construction. Fig. 6 is a fragmentary side elevation of the modified form of construction of type bar.

The type bar, designated as a whole by the reference numeral 1, comprises a solid type-block-carrying shank 2 to which side plates 3 and 3^a are riveted at 4. The side plates are preferably slightly resilient for purposes 45 which will hereinafter more clearly appear. One of the side plates 3 is provided with an upwardly extending perforated ear 5 to which a rearwardly extending link may be connected for actuating the type bar. This 50 same side plate 3 is also provided with an extension 6, which is bent transversely, as shown in Fig. 2, and extends over to the opposite parallel plate 3^a so as to form a protecting member which, when the type bar is

at rest, extends above the pivot 7 which 55 unites the type bar to its hanger 8 and serves to protect said pivot from falling dirt. Each hanger consists of a flat bar or piece of metal that lies between the two side plates 3 and 3^a, and the pivot 7 consists of a rivet passing 60 through said side plates and hanger and having a working fit in the latter. Each type bar hanger is received in a slot 9 formed in the forward face of a type bar segment 10. A threaded opening is provided in the opposite walls of each slot 9 for the reception of a set screw 11, the inner end of which bears against the stem of its associated hanger 8 to secure it in place in the segment.

Extending upwardly from each hanger is a 70 hook-like abutment or guide 12 beveled on both sides at 13 within the hook and at that portion of said hook which constitutes its working face. The bill of the hook extends upwardly and the hook itself opens toward 75 the front of the machine for co-operation with a companion guiding and repulsing member carried by the type bar, as shown in dotted lines in Fig. 1. The companion guiding and repulsing member comprises a pin 14 which 80 is loosely seated in bearings in the side plates of the type bar and extends across the opening between said plates. The heads 15 of this pin are spaced apart a greater distance than the distance between the outer faces of the 85 side plates so that the heads of the pin will not obstruct or prevent an outward movement of the plates for a limited distance as indicated in Fig. 4. Said guiding and repulsing member also comprises two independently movable plates, contacts or disks 16 supported on the pin 14, and beveled on their adjacent faces at 17 and the outer sides of which bear against the side plates 3 and 3^a of the type bar. The construction is such 95 that when the type bar moves toward the printing point the hook-like portion of the abutment 12 will be received between the beveled faces of the disks 16 on the type bar before the type bar reaches the printing position, as indicated in dotted lines in Fig. 1. When the type bar has reached this dotted line position the disks 16 would be brought into contact with the hook-like member as indicated in Fig. 3. A further movement of 100 the type bar to the printing position by the momentum of its printing stroke will cause the disks 16 to be wedged apart against the

spring pressure exerted by the side plates 3 and 3^a of the type bar as indicated in Fig. 4, thus exerting an impinging pressure against the hook-like member 12 and against the 5 beveled or wedge-like face thereof, and this pressure tends to force the type bar away from the platen as soon as pressure on the key is released. The devices also co-act to 10 form a type bar guide which acts between the pivot and the free end of the bar to prevent a lateral deflection thereof and to bring about an accurate alinement of the imprinted characters. By reason of the hook-like guide 12 coöperating with the disks 16 in the manner 15 described, there will also be a tendency to bring about a proper guiding of the type bar to prevent an undue movement thereof in a direction at right angles to the printing line should there be any lost motion at the pivotal 20 connection between the type bar and hanger. In other words, the coöperation of the devices before the type bar reaches the printing position not only tends to prevent a lateral deflection of the type bar from its proper 25 path, but also tends to prevent a longitudinal movement of the bar from around its proper pivotal axis.

In Figs. 5 and 6 I have shown a modified form of construction embodying my invention. 30 This form of the invention is the same as that previously described except that the pin 14 and conoidal disks or contacts 16 mounted thereon are omitted and conoidal contacts 18 are formed directly on the side 35 plates 3^b and 3^c, as shown in Figs. 5 and 6; the contacts 18 being struck up from the body portions of the side plates and projecting toward each other. When a type bar reaches the dotted line position the conoidal 40 contacts 18 will be brought into coöperation with the fixed abutment 12 and they will be forced away from each other against the spring tension of the side plates from which they are formed.

45 Various changes may be made without departing from the scope of my invention.

What I claim as new and desire to secure by Letters Patent, is:—

1. In a typewriting machine, the combination 50 of a type bar carrying a combined type bar guiding and repulser member intermediate its pivot and the free end of the type bar, and a type bar hanger carrying a guiding and repulser member with which the combined 55 type bar repulser and guiding member on the type bar coöperates during the last portion only of the stroke of the type bar.

2. In a typewriting machine, the combination 60 of a type bar having its heel bifurcated, a combined type bar guiding and repulser member contained between the walls of the type bar formed by the bifurcation therein, and a hanger received in the bifurcation of the type bar and having a combined type bar 65 repulsing and guiding member that coöper-

ates with the guiding and repulsing member on the type bar at the last portion of the stroke of the type bar.

3. In a typewriting machine, the combination 70 of a type bar and a hanger, one of said members being bifurcated to receive the other, the bifurcated member carrying two beveled contacts which are movable independently of each other and the other member carrying a beveled device that is brought 75 into coöperation with said beveled contacts on the bifurcated member at the last part of the printing stroke of the type bar.

4. In a typewriting machine, the combination 80 of a type bar and a hanger, one of said members being bifurcated to receive the other, the bifurcated member carrying beveled contacts that are spring pressed toward each other and the other member carrying a beveled device that is brought into coöperation 85 with said contacts and tends to separate them at the last part of the printing stroke of the type bar.

5. In a typewriting machine, the combination 90 of a type bar and a hanger, one of said members being bifurcated to receive the other, the bifurcated member carrying beveled contacts that are spring pressed toward each other by the arms of the bifurcated member and the other member carrying a 95 hook-like beveled device that is brought into coöperation with said contacts and tends to separate them at the last part of the printing stroke of the type bar, whereby said contacts and device act as combined guides and repulsers.

6. In a typewriting machine, the combination 100 of a type bar and a hanger, one of said parts being bifurcated, the type bar and hanger having abutments that are brought into contact before the type bar reaches the printing position and the bifurcated portion exerting a lateral pressure between the contacts which is effective as a repulser for the type bar.

7. In a typewriting machine, the combination 110 of a type bar and a hanger, one of said members carrying two repulser devices that move independently of the member that carries them and toward and away from each other, the other member coöperating with said repulser devices and tending to spread them apart before the type bar reaches the printing position.

8. In a typewriting machine, the combination 120 of a type bar and a hanger, one of said members carrying two repulser contacts that are beveled toward each other and move toward and away from each other, the other member being received between the contacts and coöperating therewith and tending to spread them apart before the type bar reaches the printing position.

9. In a typewriting machine, the combination 130 of a type bar, a hanger, a spring repulser

device carried by the type bar, and a rigid abutment on the type bar hanger with which said spring repulser coöperates before the type bar reaches the printing position.

5 10. In a typewriting machine, the combination of a type bar, a hanger, a combined spring type bar guide and repulser device carried by said type bar, and a rigid abutment on the hanger with which said combined spring repulser device and guide coöperates before the type bar reaches the printing position to guide the type bar and to effect a quick rebound thereof from the platen.

15 11. In a typewriting machine, the combination of a type bar, a hanger, a combined spring type bar guide and repulser device carried by said type bar, and a rigid abutment on the hanger with which said combined spring repulser and guide coöperates before the type bar reaches the printing position to guide the type bar and to effect a quick rebound thereof from the platen, the working face of one of said abutment and 20 25 guide elements being in the nature of a substantially V-shaped groove and the other element being substantially V-shaped to fit said groove.

12. In a typewriting machine, the combination of a type bar, a hanger, a combined spring type bar guide and repulser device carried by said type bar, and a rigid abutment on the hanger with which said combined spring repulser and guide coöperates 30 35 before the type bar reaches the printing position to guide the type bar and to effect a quick rebound thereof from the platen, the rigid abutment being formed as a hook-like member beveled on its working face and the 40 combined repulser and guide being formed of disks beveled on their adjacent faces and spring pressed toward each other.

13. In a typewriting machine, the combination of a type bar, the pivoted end portion 45 of which comprises two parallel spring side plates, a hanger contained between said side plates and to which said type bar is pivoted, a guide and repulser between said spring side plates and by which pressure is exerted on 50 the guide and repulser, and a fixed abutment on the hanger with which said guide and repulser coöperates at the last portion of the printing stroke.

14. In a typewriting machine, the combination of a type bar, the pivoted end portion 55 of which comprises two parallel side plates, a hanger contained between said side plates and to which said type bar is pivoted, two independently movable contact plates between 60 said side plates, and a fixed abutment which contacts with and is received between the contact plates at the last portion of the printing stroke of the type bar.

15. In a typewriting machine, the combi-

nation of a type bar, the pivoted end portion 65 of which comprises two parallel side plates, a hanger contained between said side plates and to which said type bar is pivoted, two independently movable contacts which are beveled on their adjacent sides and against which the side plates bear, and a fixed abutment that is received between said contacts at the last portion of the printing movement of the type bar and tends to spread said contacts apart.

75 16. In a typewriting machine, the combination of a type bar, the pivoted end portion of which comprises two parallel side plates, a hanger contained between said side plates and to which said type bar is pivoted, two independently movable disks which are beveled on their inner sides and against the outer sides of which the side plates bear, a pin that extends between the side plates and on which the disks are supported, and a hook-like fixed abutment that is received between said disks at the last portion of the printing movement of the type bar and tends to spread said disks apart against the pressure of said side plates.

80 85 90 17. In a typewriting machine, the combination of a type bar, the pivoted end portion of which comprises two parallel side plates, a hanger contained between said side plates and to which said type bar is pivoted, two independently movable contact plates contained between the side plates and bearing against the same, and means which tend to separate said contact plates before the type bar reaches the printing position.

18. In a typewriting machine, the combination of a type bar and a hanger, one of said members comprising two parallel side plates, and means which exert an impinging force against said side plates that tends to spread them apart before the type bar reaches the 100 105 printing position.

19. In a typewriting machine, the combination of a type bar and a hanger, one of said members comprising two parallel side plates, and a wedge that tends to separate said side 110 plates before the type bar reaches the printing position, whereby a repulser and guiding construction is provided.

20. In a typewriting machine, the combination of a series of type bars, a pair of independently movable conoidal contacts, and a coöperating abutment for each type bar, said contacts and abutment for each type bar acting as a combined type bar repulser and guide.

115 120 Signed at the borough of Manhattan, city of New York, in the county of New York, and State of New York, this 16 day of October A. D. 1906.

CHARLES E. TOMLINSON.
